(57) **CLAIM**

The ornamental design for a top sizer for a hanger, as shown and described.

DESCRIPTION

FIG. 1 is a top front perspective view of a top sizer for a hanger showing my new design;

FIG. 2 is a top plan view thereof;

FIG. 3 is a front elevation view thereof, with the back being a mirror image thereof;

FIG. 4 is a right side elevation view thereof; and,

FIG. 5 is a bottom plan view thereof.

The broken line showing of an opening for receiving a hook of the hanger is for illustrative purposes only and forms no part of the claimed design.
